UNITED STATES PATENT OFFICE

HORACE W. HALL, OF NEWTON, MASSACHUSETTS, ASSIGNOR, BY MESNE ASSIGNMENTS, TO DOROTHY K. HALL, OF NEWTON, MASSACHUSETTS

BOAT CONSTRUCTION

Application filed August 7, 1929. Serial No. 384,018.

This invention relates to improved boat construction or other floating apparatus, and particularly to speed boats to take out-board motors, and improved methods of constructing same.

One of the objects of my invention is to make the sides and stern of a speed boat from two halves, each half extending from tip of bow to middle of stern and being an entity itself.

These two sides are formed independently of the rest of the boat, being composed of an outer panel of several plies of thin wood veneer and an inner panel of the same material with a filler of cork, balsa wood or other like buoyant material between. The said plies and filler are glued together with waterproof glue, and while the glue is still plastic the whole is bent under pressure into the required shape, the pressure being applied until the glue hardens and is thoroughly set.

Each half being separately assembled into permanent shape, it is itself rigid and rigorous and requires no ribs or other support to maintain its shape, thus saving cost in assembly of the boat and lessening considerably the time and labor required at present to construct the sides.

Joints and caulking, heretofore necessary to keep the sides and stern from leaking, are dispensed with. Even though the bottom of the boat leaks or is stove in, my sides and stern, being an entity themselves will support the motor and save the same from immersion and will serve as a float which will support about twice the number of people the boat is built to carry. Also the bottom may be taken out and repaired without disturbing the sides.

Heretofore in speed boats designed to have outboard motors fastened to them the stern is a separate piece fastened to the two sides, thereby forming two square joints where the sides and stern are joined. As the outboard motor is attached at the center of the stern the vibration it causes when running tends to loosen or open these joints which are under a continual strain. It has been impossible to reinforce these joints so as to pre-

vent some leakage occurring after the boat has been in use a short time.

With my construction, however, I have done away with this leakage. Only a single joint is formed at the stern and this is a spliced joint which itself is strong and leak-proof. I further strengthen it by covering it with cleats or plates of reinforced wood approximately one inch thick on both the outside and inside, which take the screws of the motor attachment. As these plates extend from one side to the other the screws which hold the motor attachment are partly on one side and partly on the other, and therefore the weight of the motor attachment is equally divided between the two sides thus dividing vibration. As the sides are each integral they are strong enough to withstand this vibration and there is no tendency for the single joint formed to develop a leak.

There are preferably 3 plies of wood veneer used in the construction of both the outside and inside panels, the plies being cross banded. They should be thin enough to bend freely without internal strain and without steaming, and I have found that plies of $\frac{1}{8}$ " thickness or less are satisfactory. These plies not only furnish the necessary stiffening and strength; but they also give the sides interiorly and exteriorly a natural beauty of finish by the use of mahogany or finished wood for the exposed layers, the other veneers being of any suitable cheaper wood.

The filler of buoyant material, which should be about 1" thick, not only furnishes buoyancy, but is also a medium of strength because being glued to the veneer plies it becomes an integral part of the side. In using the term "buoyant material" I mean to include any material or substance having a specific gravity of 0.30 or less such as cork, balsa wood, etc.

The results attained by my new construction as compared with boat construction heretofore known are economy of manufacture, increased speed obtainable due to lightness and buoyancy, safety due to the sides being made a separate entity from the bottom, and

water tightness due to strengthening and reducing the number of joints.

With the above and other objects in view which will more readily appear as the nature of the invention is better understood, the same consists in the novel construction, combination and arrangement of parts herein-after more fully described, claimed and illustrated in the accompanying drawings.

In the drawings:

Figure 1 is a perspective view of my boat constructed in accordance with the present invention.

Figure 2 is a side elevation of my boat, with a portion at the end broken away.

Figure 3 is a longitudinal sectional view on the line 3—3 of Figure 1.

Figure 4 is a section taken on the lines 4—4 of Figure 2.

Figure 5 is a section taken on the lines 5—5 of Figure 2.

Figure 6 is a fragmentary sectional view showing the material used in the construction of the sides of my boat.

Figure 7 is a fragmentary perspective view of the rear end of my boat.

As illustrated the sides 11 of my boat consist of several plies of one-piece thin wood veneer 12 and a filler 13 of cork, balsa wood or other buoyant material. I use preferably three plies of veneer on each side of the filler, although the number of plies may be varied, and the filler is preferably about one inch thick. These layers of veneer and filler are glued to each other with an adhesive substance such as waterproof glue, and while the glue is still plastic the whole side structure is bent or moulded under pressure to form the side and part of the stern of a boat, extending from bow to the center of the stern, as shown in Figure 1 of the drawings. The pressure is applied until the glue becomes hard and set, which gives me an integral structure forming a complete side and part of the stern of a boat, which in itself is firm and rigid.

Before assembling the boat proper, the two side units 11 are brought together and joined with a waterproof glue or other adhesive at the bow and stern, and pressure is applied at the points of union until the glue has firmly set. The two sides are now an integral structure, and a very strong one. The wooden cleats or plates 17 are placed on the outside and inside of the boat and bolted as at 18 to the two stern portions for reinforcement purposes as previously explained.

In assembling the boat proper a metal strip 16 covers the joint at the bow, extending from the top part way under the bottom. In order that the bottom 20 of my boat may be more durable, hold its shape better and have less skin friction when the boat is speed-ing, I preferably make the bottom of metal such as duralumin. It is turned up at the

edges to form flanges 21 and is tightly held to the sides 11 of the boat by bolts 22 which extend through said sides and flanges. These flanges are parallel to the sides of the boat for their full length to conform to the varying shape of said sides. Gaskets, not shown, may be used to insure water tightness, and some calking may be necessary between the sides and flanges.

As shown in Figures 2 and 3 of the drawings it is customary in speed boats to step the bottom a little more than half way back from the bow, and this step is made by a cross member 24. The keel 25 is a prolongation of the keel stem 15 and extends the length of the bottom. The cross member 24 is mortised as at 26 to receive an end of the keel 25 as shown in Figure 3. Bolts 27, preferably countersunk, extending through the cross member and both portions of the keel make a tight union here. This cross member 24 is also attached to the metal bottom by bolts 28.

At the rear or stern portion of the boat an angle iron 30 extends from one side to the other just below the cleats 17, bent to conform to the shape of the stern. The bottom 20 is extended as at 20a beyond the stern to prevent cavitating, and is provided with a recess 20b to accommodate the propeller shaft. The deck is given the numeral 31 and has a heading 32. The sides 11 of the boat are provided with top rails 33 of finished wood.

While a specific embodiment of the invention has been illustrated and described, the invention is not to be considered as limited to the particular combination and arrangement of parts as above described, except as limited in scope by the appended claims.

What I claim is:

1. Structure for the sides of a boat comprising a plurality of plies of wood veneer on the outside, a buoyant material for the center and a plurality of plies of wood veneer on the inside, said plies and buoyant material being united together to form an integral whole.

2. Structure for the sides of a boat comprising an outside panel, an inside panel and a filler, said panels embodying a plurality of plies of wood veneer glued together, said filler embodying a buoyant material glued to and between said panels.

3. Structure for the sides of a boat comprising a plurality of thin strips of one-piece wood veneer on the outside and inside and a filler of buoyant material between said strips, the whole being permanently united together.

4. Structure for the sides and stern of a boat comprising a plurality of thin strips of flexible, one-piece wood veneer on the outside and inside, and a filler of balsa wood between said strips, the whole being united by a waterproof substance.

5. A boat comprising a bottom and two

5 sides joined together at the bow and stern and fastened to said bottom, each side embodying one-piece plies of wood veneer extending from the bow the length of the boat and forming part of the stern, and a cleat fastened to each of said sides covering the point of jointure at the stern.

10 6. A boat comprising two sides, each side extending from the bow to and having a sharp bend therein thereby forming part of the stern, a metal bottom having a flange, and means to fasten said sides to said flange.

15 7. A boat comprising a metal bottom and two sides, each side comprising a plurality of plies of wood veneer and a layer of buoyant material between said plies, said plies and layer being permanently united together to form an integral whole and being so shaped as to also form the stern, said bottom having 20 a flange adapted to lap over part of said sides and means attached to said flange and sides to hold them firmly together.

25 8. A boat comprising a metal bottom and two sides, each side comprising a plurality of plies of wood veneer and a layer of buoyant material between said plies, said plies and layer being permanently united together to form an integral whole and being so shaped as to also form the stern, said bottom having 30 a flange adapted to lap over part of said sides and running parallel to said sides at all points from stem to stern, and means to hold said flange and sides together.

35 9. A boat comprising a bottom and two sides, each side extending from the bow the length of the boat and forming part of the stern, the two sides forming a joint at one end at the center of said stern, an outside cleat and an inside cleat each covering and overlapping 40 said joint and fastened to both of said sides.

45 10. The method of forming the side of a boat which comprises laying together a plurality of plies of wood veneer and a filler of buoyant material after first treating with an adhesive, bending the whole by pressure to the required shape and keeping under pressure until the adhesive has set.

50 11. The method of forming the side of a boat extending from the bow to, and forming part of, the stern, which comprises uniting together with an adhesive a plurality of plies of wood veneer with a filler of buoyant material intermediate the outside and inside plies, and molding the whole under pressure to the required shape while said adhesive is in plastic condition, and continuing the application of pressure until the adhesive has set.

55 12. The method of forming the side of a boat in one piece extending from the bow to and forming part of the stern, which comprises treating a plurality of plies of one-piece wood veneer and a layer of buoyant material with a waterproof adhesive, laying said plies together one upon the other with said 60 layer of buoyant material intermediate the

top and bottom plies, molding the whole under pressure to the required shape while said adhesive is in plastic condition, and continuing the application of pressure until said adhesive has set.

70 13. The method of forming the side of a boat which extends from the bow to the stern and forms a part of said stern, comprising uniting together with a waterproof glue a plurality of one-piece plies of wood veneer with a filler of buoyant material between them, molding the whole under pressure while said glue is in plastic condition to the required shape and continuing the pressure until said glue has set.

75 14. The method of forming the side of a boat which comprises laying together a plurality of plies of wood veneer and a filler of buoyant material after first treating said plies and filler with a waterproof adhesive, molding the whole under pressure to the required shape while the adhesive is in plastic condition, and keeping under pressure until the adhesive has set.

80 15. A boat comprising a bottom, sides, and a stern of such width that it is adapted to have an outboard motor fastened to it, said sides and stern being composed of two parts joined together, said parts embodying a plurality of plies of wood veneer united together 90 and bent to the desired shape whereby said sides and stern are formed of said two parts.

95 16. A boat having a substantially pointed bow and a broad stern, comprising a bottom and a plurality of sides, said sides embodying a plurality of plies of wood veneer united together, said plies being so bent whereby the stern is formed of the same plies that form the sides.

100 17. A boat comprising a bottom and a plurality of sides fastened to said bottom, each side embodying a plurality of plies of wood veneer united together, said plies extending from the bow to and forming part of the stern, said stern being sufficiently broad to accommodate an outboard motor.
